UNITED STATES PATENT OFFICE

2,008,397

SIGNAL SYSTEM FOR ELEVATORS

Frank E. Lewis, Chicago, Ill., assignor to Westinghouse Electric & Manufacturing Company, a corporation of Pennsylvania

Application August 21, 1931, Serial No. 558,527

17 Claims. (Cl. 177—336)

My invention relates to "flash" signal systems for elevators and more particularly to such systems as embody means for indicating the existence of registered calls for service.

- 5 In many modern elevator systems, the cars are operated from terminal to terminal on a predetermined schedule during the day time. At night or when traffic is light and it is not necessary to run the cars continuously, they are usually 10 parked at the bottom, and a night bell or buzzer is connected by a switch to the signal system so that upon the registration of a call for service at any of the landing floors the bell will ring to notify the attendant on duty that he should run 15 the car to the floor at which the call exists. Heretofore, in addition to the night bell or buzzer, it has been customary to mount an annunciator in one or more of the cars to indicate the floor at which the registered call exists, so that the night 20 attendant may know exactly which floor to run to in answering a registered call. The use of an annunciator requires at least two wires for each floor, which, in very tall buildings, requires a large number of wires running to the car.
- 25 In my improved system, I propose to provide a night buzzer that may be connected to the signal system for calling the attention of the night attendant to the registration of calls for service, and to also dispose in each car a pair of indicating devices, such as an "up" lamp and a "down" 30 lamp for indicating whether the registered call is above or below the car, assuming that the cars are standing at their parking floor. With this system, a night attendant upon hearing the buzzer can enter any car and start on a trip in the direction of the registered call. As soon as he answers the call, the "up" or "down" signal lamp will be restored to its non-indicating condition, and the attendant will be thereby informed that 35 no more registered calls exist. If in the meantime any additional call is registered above or below the car, the "up" or the "down" signal lamp will so inform the operator.

Very often during the day time, the traffic will 40 not be sufficient to warrant running the cars according to a predetermined schedule. In such cases, the "up" and "down" signals may be connected to the signal system and the cars operated as they are at night.

Furthermore, my improved system may be employed to advantage in rush hours when passengers are leaving the building in large numbers at about the same time. In such instances, the operation of the cars on a predetermined 45 schedule may be abandoned and the cars simply

run to the farthest call, as indicated by the "up" or the "down" signal device, and then returned to the unloading floor.

The object of my invention, in general, is to provide a system for indicating the existence of registered calls for service which shall be simple in operation and easily installed and maintained.

A more specific object of my invention is to provide a signal system of the character indicated in which the number of wires or indicators necessary for its operation may be reduced to a minimum.

Other objects of my invention will, in part, be obvious, and will, in part, appear hereinafter.

For a better understanding of my invention, reference may be had to the accompanying drawings, in which:

Figures 1 and 2 collectively constitute a diagrammatic representation of the circuits and apparatus of an elevator signal system embodying my invention.

Fig. 3 is a straight line diagram of the circuit for the relays which control the operation of the "up" and the "down" signal lamps.

Referring more particularly to the drawings, I have illustrated therein a signal system for a pair of elevator cars A and B to be operated in their respective hatchways (not shown) between a plurality of floors by car attendants in the usual manner. While only two cars are shown, as operating between five floors it will be understood that my system may be applied to any number of cars operating between any number of floors.

The cars are shown as provided with a "flash" signal system in which a stop signal lamp is disposed on each of the cars for indicating to the attendant when a stop is to be made to take on passengers. The stop signal lamp on car A is designated as AL, and that on car B as BL.

In order that waiting passengers at the floor landings may cause the stop signal lamps in the cars to be operated to indicate a stop as the cars approach their floors, push buttons 1D, 2D, 2U, 3D, 3U, 4D, 4U and 5U are located at the floor landings in position to be operated by the waiting passengers.

Associated with passenger operated push buttons are push button relays 1DR, 2DR, 2UR, 3DR, 3UR, 4DR, 4UR and 5UR for maintaining the calls after the buttons are pressed until they are answered, thereby making it unnecessary for the passengers to hold the buttons in a depressed condition until the cars make the answering stops. Thus it will be seen that the push buttons and associated relays provide a means whereby the

passengers may register a stop call and then wait until some car answers it.

Each of the push button relays is provided with two energizing coils wound in opposition to each other in such manner that one of the coils when energized causes the relay to be actuated to close its contact members, while the operation of the other coil opposes the effect of the first coil and thereby causes the relay to be restored to its normal condition.

In accordance with my invention, each car is provided with an "up" signal device and a "down" signal device for indicating to the car attendant that a registered call exists above or below the car, and that he should move the car in that direction to answer such call. The "up" and the "down" signal devices are illustrated as an "up" panel and a "down" panel disposed in front of corresponding electric lamps so that when a lamp is energized, the corresponding direction word will be illuminated. The "up" lamp in car A is designated as AU and the "down" lamp as AD. In car B, the "up" lamp is BU and the "down" lamp BD. For convenience, these lamps will be called "night" lamps. A switch 12 in car A and a switch 13 in car B are provided for connecting the night lamps to the signal system when desired.

A pair of relays 14 and 15 are provided for controlling the night lamps AU and AD in car A, and a second pair of relays 16 and 17 are provided for controlling the night lamps BU and BD in car B.

At night or when there is practically no traffic, it is a usual practice to park the cars at the exit terminal and leave only one attendant to answer such occasional calls as may occur. In order to call the attention of such attendant to the fact that a passenger has registered a call for service upon one of the passenger-operated push buttons, I have provided a night bell or buzzer 20 which may be disposed in any suitable position such as at the parking station or in one of the cars, for instance as shown in car A. A transformer T is provided for energizing the buzzer. The primary coil of the transformer may be connected to a suitable source of alternating electric current (not shown) and the secondary coil is disposed in a circuit which is common to both the push buttons and the buzzer. A switch 21 is provided adjacent to the transformer for connecting it to its source of power when the buzzer is to be placed in service.

In order that the various circuits for the push buttons and the signal devices may be connected for operation in accordance with the movements of the cars, the cars A and B are provided, respectively, with floor selectors FSA and FSB. The floor selectors are similar to those usually employed in elevator signalling systems and may be located in any suitable place such as in the pent house.

The selector FSA is provided with a set of "up" contact segments and a set of "down" contact segments. The "up" contact segments are arranged in groups under brushes CU, DU and FU and the "down" contact segments are arranged in groups under brushes HD, ID and JD that are mounted upon a movable arm MA which traverses the contact segments. Similarly, the selector FSB is provided with "up" contact segments arranged in groups under brushes MU, NU and OU and "down" contact segments arranged in groups under brushes RD, SD and TD that are mounted upon a movable arm MD.

The movable arm on each selector is operated by a screw S which is driven by some part of the operating mechanism of the car which the selector serves. The frictional engagement between the arms and their operating screws causes the arms to bear upon the "up" contact segments when the cars are travelling upward and upon the "down" contact segments when the cars are moving "down".

The group of contact segments under the brush CU connects the "flash" signal lamp AL in car A with the floor push buttons. The group includes a contact segment for each of the 2nd, 3rd, 4th and 5th floors and a continuous strip that is electrically connected to the signal lamp AL.

The group of contact segments under the brush DU connects the circuits for restoring the push button relays, and includes a continuous strip connected to the supply conductor L2 and contact segments for the 2nd, 3rd, 4th and 5th floors.

The group of contact segments under the brush FU is provided for connecting certain circuits controlled by the push button relays for controlling the lighting of the "up" night lamp.

The "up" side of selector FSB for car B is similar to that for car A. The "down" side of each selector comprises a duplicate of "up" contact members except for a reversal of the order of the contact segments and a slight change in the relative position of the various groups to compensate for the different direction in which the car approaches the floor.

It should be noted here that the brushes FU and HD on the floor selector FSA leading to the night lamp relays 14 and 15 are mounted on springs which cause these brushes to bear continuously upon the contact segments under them, regardless of the direction of operation of the car. The brushes OU and RD on the floor selector FSB are also mounted upon springs so that they will continuously bear upon the contact segments thereunder, regardless of the direction of operation of the car.

For convenience, the invention is described in connection with a "flash" signal system, but it may be applied just as readily to a signal control system wherein the operation of a floor push button at a floor landing by an intending passenger serves to stop the car when it arrives at that floor in the corresponding direction. Inasmuch as such a signal control system is disclosed in my co-pending application, Serial No. 388,310, filed August 26, 1929, and assigned to the Westinghouse Electric & Mfg. Company, no further description of it will be given here.

The invention may be understood best by an assumed operation thereof. Assuming that the cars A and B are being operated under a predetermined schedule without the night lamps or night buzzer being connected to the signal circuit, that car A is moving upwardly and that an intending passenger at the third floor, desiring to board an up moving car, presses the up push button 3U, then a registered call will exist to light the signal lamp AL in the car as the car nears the third floor to indicate to the attendant that he should stop the car at the third floor.

The pressing of the push button 3U registers the stop call by energizing the push button relay 3UR through a circuit extending from a source of direct current represented by the supply conductor L1 through conductor 31, the secondary coil of transformer T, conductor 31, buzzer 20, conductor 32, the contact members of push but-

ton 3U, conductor 33, the holding coil 34 of relay 3UR and conductor 35 to the supply conductor L2.

It should be noted here, that the secondary coil of the transformer T and the coil of the buzzer 20 are always in series with the circuit through the contact members of the push buttons, but that the coil of the buzzer is so designed that it will not operate the buzzer on the direct current that flows through it when the button is pressed, but

10 that it will operate the buzzer upon operation of the push button when the switch 21 is closed to energize the transformer T and cause an alternating current to be impressed upon the buzzer circuit.

15 The energization of the push button relay 3UR closes its contact members a to complete a self-holding circuit for itself extending from the supply conductor L1 through conductor 37, contact members a of relay 3UR, conductor 38, the coil 34 and conductor 35 to the supply conductor L2.

20 The energization of the push button relay 3UR also energizes the contact segment 40 on the floor selector FSA and the contact segment 48 on the floor selector FSB. As car A approaches the third floor, its brush CU completes a circuit for lighting the signal lamp AL in the car to warn the attendant to make the third floor stop. This circuit extends from supply conductor L1, through conductor 37, the contact members a of relay 30 25 3UR, conductor 41, contact segment 49, brush CU, contact strip 42, conductors 43 and 44, the signal lamp AL, and conductor 45 to supply conductor L1.

25 As car A comes to a stop at the 3rd floor, its brush DU engages the contact strip 49 and thereby completes a circuit for restoring the push button relay 3UR to its normal condition, which circuit extends from supply conductor L1 through conductor 37 the contact members a of relay 3UR, conductor 38, restoring coil 50, conductor 51, contact segment 49, brush DU, contact strip 52 and conductor 53 to supply conductor L2. The energization of restoring coil 50 overcomes the energized coil 34 and releases the relay 3UR to its normal position in which its contact members a are open.

30 Thus, it is seen that the cars may be operated under the flash signal system without the night buzzer or the night lamps.

35 Assuming now that practically all of the tenants have left the building and that the cars are parked at the lower or exit terminal with only one attendant to answer such calls as may occasionally occur. Under these conditions the switch 21, at the transformer T, should be closed to supply alternating current to the transformer so that the pressing of a push button by a passenger at a floor landing will operate the buzzer. The switches 12 and 13 are also closed for connecting the "up" and the "down" night lamps in the cars to the signal system.

40 Assuming now, that a passenger at the fourth floor, desiring to travel upwardly, presses the "up" button 4U to register a call for service at that floor. The pressing of the button 4U effects the operation of the buzzer 20 to call the attention of the attendant to the existence of a registered call for service, it also effects the lighting of the "up" lamp AU in car A and the "up" lamp BU in car B to indicate that the call is above the cars and it also prepares a circuit for lighting the "stop" signal lamp in the first car to approach in the direction of the call.

45 The closing of the contact members on button 4U completes a circuit for energizing relay 4UR which extends from supply conductor L1 through

5 conductor 30, the secondary coil of transformer T, conductor 31, the coil of buzzer 20, conductor 32, the contact members of push button 4U, conductor 55, the holding coil 56 of relay 4UR and conductor 57 to supply conductor L2. This circuit 5 operates the relay, but inasmuch as the buzzer coil is so designed as not to be affected by the direct current flowing through the push button circuit, the buzzer will not yet be operated.

10 The closing of the contact members a on the relay 4UR also completes a circuit through the secondary coil of the transformer T for operating the buzzer 20, which circuit extends from the secondary coil of the transformer T through conductor 34, the coil of buzzer 20, conductor 32, the contact members of push button 4U, conductors 55 and 59, the contact members a of relay 4UR and conductors 58, L1 and 30 to the secondary coil of the transformer T. Inasmuch as the switch 21 to the transformer T is closed, an alternating current will be induced in the circuit just described sufficient to operate the buzzer 20 as long as the button is pressed and thereby notifies the night attendant that a registered call exists.

15 The closing of the contact members a on the relay 4UR also completes a self-holding circuit for that relay extending from supply conductor L1 through conductor 58, contact members a of relay 4UR, conductor 59, coil 56 and conductor 57 to supply conductor L2.

20 The closing of the contact members a of push button relay 4UR also energizes the "up" contact segment 61 on the floor selector FSA and the "up" contact segment 62 on the floor selector FSB to effect the lighting of the stop signal lamp 25 in that car which first approaches the fourth floor, in the direction of the call.

25 The operation of the relay 4UR also opens its normally closed contact members b and c for the purpose of causing operation of the "up" night 30 lamps AU and BU. When no registered stop call exists, the night lamp relays 14, 15, 16 and 17 are maintained in an energized condition by circuits which extend through normally closed contact members on the push button relays. When an "up" or a "down" stop call is registered, it de-energizes the corresponding night lamp relays which, in turn, close their contact members to light the corresponding night lamps. For instance, when both cars are at the lower floor, the 35 circuit for maintaining the "up" night lamp relays 14 and 16 in an energized condition extends from supply conductor L1 through conductors 65 and 66, contact members b of relay 3UR, conductor 67, the contact members b of relay 4UR, conductor 68, the contact members b of relay 4DR, conductor 69, the contact members b of relay 3UR, conductor 70, the contact members b of relay 3DR, conductor 71, the contact members b of relay 2UR, conductor 72, the contact members b of relay 2DR and conductor 73 to junction point 74, one branch extending through conductor 75, contact segment 76 on floor selector FSA, contact brush FU, conductor 81, the coil of night lamp relay 14, and conductor 82 to supply conductor 65 L2; and the other branch extending from the junction point 74 through conductor 84, the contact segment 85 on floor selector FSB, the contact brush OU, conductor 91, the coil of relay 16 and conductor 92 to the supply conductor L2. Thus, both relays remain energized and thereby prevent lighting of the "up" night lamps until a call for service is registered on the push buttons.

70 The circuit including the conductors 67, 68, 69, 71, 72 leading to the "up" night lamp re- 75

lays 14 and 16 may be called the energized "above" circuit. The circuit including the conductor 125 leading to the "down" night lamp relays 15 and 17 may be called the energized "below" circuit.

- 5 If the cars move upwardly, the circuit for maintaining the up night lamp relays in an energized condition is transferred from contact segment to contact segment by the brush FU and the brush OU. The contact segments under the 10 brushes FU and OU are electrically connected to the push button relays, in such manner as to eliminate the relays for the lower floors from the circuit as the cars move upwardly as will be plainly seen by reference to the straight line diagram 15 of Fig. 3.

Referring again to the energization of the relay 4UR, the opening of its contact members *b* opens the circuit for energizing the up night lamp relays 14 and 16, thereby deenergizing these relays 20 and closing their contact members to light the night lamps.

The closing of the contact members on relay 14 for car A completes a circuit for lighting the up night lamp in car A, which extends from supply 25 conductor L1 through conductor 95, the contact members of relay 14, conductor 96, night lamp AU, conductor 97, switch 12 and conductor 45 to supply conductor L2.

The deenergization of the night lamp relay 16 30 causes the up night lamp BU in car B to be lighted by a circuit which extends from supply conductor L1 through conductor 106, the contact members of relay 16, conductor 101, lamp BU, conductor 102, switch 13 and conductor 103 to supply conductor 35 L2. Therefore, the up night lamps AU and BU in the cars A and B, respectively, are lighted to indicate that a registered stop call for service exists at a floor above the car, just which floor is not indicated but the attendant can enter one of 40 the cars and run up until the "stop" signal lamp in the car lights to indicate the floor at which the call exists.

Let us assume that the attendant enters car B and runs it upwardly to answer the registered 45 call, as the car moves upwardly the brush OU on floor selector FSB leaves contact segment 85 corresponding to the first floor and successively engages the contact segments 86 and 87 for the 2nd and 3rd floors to maintain the illumination of 50 the "up" night lamp in car B.

As car B nears the fourth floor, the flash lamp brush MU on the floor selector FSB engages the 55 energized contact segment 62 and thereby completes a circuit for lighting the flash signal lamp BL in car B, which circuit extends from supply conductor L1 through conductor 58, the contact members *a* of relay 4UR, conductor 108, contact segment 62, brush MU, contact strip 109, conductor 43, lamp BL, and conductor 103 to supply 60 conductor L2.

The lighting of the flash signal lamp BL causes the operator to stop the car at the 4th floor landing. As the car comes to a stop at the 4th floor landing, the restoring brush NU bridges the 65 contact segment 107 and the contact strip 110, thereby completing a circuit for energizing the restoring coil 111 of push button relay 4UR to overcome the holding coil 56 and restore the relay to its inactive position. This circuit extends 70 from supply conductor L1 through conductor 58, the contact members *a* of relay 4UR, conductor 59, restoring coil 111, conductors 112 and 113, contact segment 107, brush NU, contact strip 110 and conductor 114 to supply conductor L2.

75 The restoration of the push button relay 4UR

to its normal inactive position closes its contact members *b* and thereby completes the previously described circuit for again energizing the night lamp relays 14 and 15, thereby opening the circuits for the up signal lamps AU and BU in the cars A and B.

Assuming now that while car B is in the upper part of its hatchway, a waiting passenger at the second floor landing presses the "up" button 2U at that landing, then a "stop" call will be registered to stop the car at that floor on its next "up" trip and the "down" night lamp BD in car B will be lighted to indicate to the attendant that a registered call exists at a floor landing below the car. If the night lamps in car A, at the first floor, are still connected to the signal system, the "up" lamp AU in that car will also be lighted to indicate the existence of an "up" stop call.

The pressing of the button 2U completes a circuit for energizing the push button relay 2UR, 20 which circuit extends from supply conductor L1 through conductor 38, a secondary coil of transformer T, conductor 31, buzzer 20, conductor 32, the contact members of "up" push button 2U, coil 115 of relay 2UR and conductor 116 to supply conductor L2.

Upon being energized, the relay 2UR closes its contact members *a* and opens its contact members *b* and *c*.

The closing of the contact members *a* of relay 2UR completes a self-holding circuit extending from conductor L1 through conductor 106, the contact members *a* of relay 2UR, conductor 117, coil 115, and conductor 116 to supply conductor L2.

The closing of the contact members *a* of relay 2UR also completes a circuit for operating the buzzer 20 by alternating current, as long as the push button is held closed, which circuit extends from a secondary coil of transformer T through conductor 31, buzzer 20, conductor 32, the contact members of push button 2U, conductor 117, the contact members *a* of push button relay 2UR and conductors 106, L1 and 30 to the secondary coil of the transformer.

The closing of the contact members *a* of relay 2UR also energizes the "up" signal contact segment 118 on floor selector FSA and the corresponding contact segment 119 on floor selector FSB to prepare a circuit for lighting the "stop" flash lamp on the first car to approach the second floor on an up trip.

Inasmuch as car B is at the upper end of its shaft, the opening of the contact members *c* on the relay 2UR opens the circuit that energizes the night lamp relay 17 for car B. Upon being deenergized, relay 17 closes its contact members and thereby completes the circuit for lighting the "down" lamp BD in car B, which circuit extends from supply conductor L1 through conductor 120, the contact members of relay 17, conductor 121, "down" night lamp BD, conductor 122, switch 13, and conductor 103 to supply conductor L2. Thereupon, the night lamp BD in car B is lighted, indicating to the attendant that he should run the car down to a registered stop call below.

As car B descends, its brush RD passes over the down contact segments under that brush.

When car B reaches the second floor on its down trip, its brush RD passes from the open portion of the circuit caused by the open contact members *c* on relay 2UR and engages the contact segment 123, thereby completing a circuit for energizing the night lamp relay 17 to extinguish

the "down" night lamp BD, which circuit extends from supply conductor L1 through conductor 124, the contact members c of relay 1DR, conductors 125, 126 and 127, the brush RD, conductor 128, 5 the coil of relay 17 and conductor 129 to supply conductor L2.

When the brush RD passes from the open portion of the circuit of relay 17, the brush OU enters the open portion of the circuit for relay 16, 10 thereby deenergizing relay 16 which causes the "up" lamp BU to be illuminated, thus indicating that the call is now above the car and that the car should be reversed to answer it.

The circuit for "up" lamp BU extends from supply conductor L1 through conductor 100, the contact members of relay 16 and lamp BU to the supply conductor L2, as previously described.

Upon noting the "up" lamp signal, the attendant reverses the car and starts upwardly. Thereupon, the brush MU engages the contact segment 119 to light the stop "flash" lamp BL for the second floor up stop, by way of a circuit extending from supply conductor L1, through conductor 106, the contact members a of relay 2UR, conductors 130 and 131, contact segment 119, brush MU, contact strip 109, conductor 43, lamp BL and conductor 103 to supply conductor L2.

As the car comes to a stop at the second floor in answer to the "up" call registered by the push button 2U, the brush NU engages the contact segment 132 thereby energizing the coil 133 of relay 2UR to restore that relay for the purpose of cancelling the registered call and extinguishing the "up" signal lamp BU in car B. The circuit for the coil 133 extends from supply conductor L1 through conductor 106, contact members a of relay 2UR, conductor 117, coil 133, conductors 134 and 135, contact segment 132, brush NU, contact strip 110 and conductor 114 to supply conductor L2.

The closing of the contact members b of the restored relay 2UR restores the circuit previously described for energizing the "up" night lamp relay 16 to open its contact members and thereby extinguish the "up" lamp BU in car B.

Thus it will be seen that I have provided a night lamp signal system in which the attendant may be notified when a registered call exists and whereby "up" and "down" night lamps in the 50 cars are lighted to indicate to the attendant whether the call exists above or below this car.

It will be observed also that the registration of calls both above and below the car will cause both night lamps in the car to light to indicate the 55 existence of such calls regardless of the direction in which the car is moving.

It will also be observed that my new system may be employed with considerable advantage at any time when the cars are not being run steadily upon a prearranged dispatching system. Furthermore, it will be seen that I have provided a "night" buzzer and signal system which require comparatively few electrical conductors or wires, and which are so simple that they may be readily 65 installed and maintained in operation.

While I have illustrated and described only one specific embodiment of my invention, I realize that it is susceptible of various modifications and I do not desire to be restricted otherwise than as 70 defined in the appended claims.

I claim as my invention:

1. In a signal system for an elevator car operable past a plurality of floor landings, passenger-operated means for registering calls for service at the landings and means operably responsive to the position of the car for indicating directly whether a registered call is above or below the car.

2. In a signal system for an elevator car operable past a plurality of floor landings, passenger-operated means for registering calls for service at the landings, an "above" indicating device on the car, and means operably responsive to the registration of a call and to the position of the car for causing said devices to indicate whether the landing at which the registered call exists is above or below the car.

3. In a signal system for an elevator car operable past a plurality of floors, passenger-operated means for registering calls for service at the landings, and means operably responsive to the registration of a call and to the position and operation of the car for continuously indicating directly the existence of the registered call and the direction of the landing at which it exists with reference to the position of the car until the call is answered.

4. In a signal system for an elevator car operable past a plurality of floor landings, passenger-operated means for registering "up" calls for service at the landings, passenger-operated means for registering "down" calls for service at the landings, and means operably responsive to the registration of an "up" call for service or a "down" call for service and to the position of the car for indicating directly to the attendant whether the registered call is above or below the car.

5. In a signal system for an elevator car operable past a plurality of floor landings, passenger-operated means for registering calls for service at the landings, means operably responsive to the position of the car for indicating directly whether a registered call is above or below the car, and means operably responsive to operation of the car in answering the registered call for restoring the call registering means and the indicating means to their inactive condition.

6. In a signal system for an elevator car operable past a plurality of floor landings, passenger-operated means for registering calls for service at the landings, an indicating device on said car, circuits for said indicating device, an "up" relay and a "down" relay disposed when deenergized to close said circuits, to operate said indicating device, circuits for maintaining said relays in energized condition, means operably responsive to the position of the car and to the call registering means for deenergizing a relay upon registration of a call for operating the indicating device to indicate whether the registered call is above or below the car.

7. In a signal system for an elevator operable past a plurality of floors, passenger-operated means for registering calls for service at the landings, a "call above" indicating device and a "call below" indicating device on the car, and means operably responsive to the registration of a call and to the position of the car for continuously operating the said indicating devices to indicate the existence of the registered call and the direction of the landing at which it exists with reference to the position of the car until the call is answered.

8. In a signal system for an elevator car operable past a plurality of floors, a passenger-operated means for registering calls for "up" service at the floors, a "call above" indicating device and a "call below" indicating device on

the car, and means operably responsive to the registration of an "up" call and to the position of the car for operating the "call above" device when the car is below that floor and for operating the "call below" device when the car is above that floor.

9. In a signal system for an elevator car operable past a plurality of floors, passenger operated means for registering calls for "down" service at 10 the floors, a "call above" indicating device and a "call below" indicating device on the car, and means operably responsive to the registration of a "down" call and to the position of the car for operating the "call above" indicating device when 15 the car is below the floor of the registered "down" call, and for operating the "call below" indicating device when the car is above the floor of the registered "down" call.

10. In a signal system for an elevator car serving a plurality of floors; passenger operative means at each floor for registering "up" calls for service and "down" calls for service; an "above" signal device and a "below" signal device in said car, means responsive to the operation of any 20 passenger operative means at floors above the position of said car for operating said "above" signal device and responsive to the operation of any passenger operative means at floors below the position of said car, contemporaneous with operation of the "above" signal device, for operating the "below" signal device at the same time.

11. In a signal system for an elevator car serving a plurality of floors, a passenger operative switch at each of said floors, an "above" signal device and a "below" signal device on said car, and means responsive to an operation of any 25 switch at a floor above said car for operating said "above" signal device and responsive to an operation of any switch at a floor below said car contemporaneous with operation of a switch at the 30 floor at which said car is positioned.

12. In a signal system for an elevator car operable past a plurality of floors, a passenger operative switch at each of said floors for registering calls for service, an "above" signal device and a 35 "below" signal device on said car, and means responsive to the operation of any switch at a floor above said car for operating said "above" signal device continuously while said car is below the floor corresponding to said operated switch, for 40 discontinuing operation of said "above" signal device while the car is at said floor and for operating said "below" signal device continuously if said car continues its movement above said first 45 mentioned floor without answering the call registered by said operated switch.

13. In a signal system for a plurality of elevator cars operable past a plurality of floors, a switch at each floor common to all the cars for 50 registering calls for service, an "above" signal

device and a "below" signal device in each car, means responsive to an operation of any switch for operating the "below" signal device of all cars above the floor at which the operated switch is located and for operating the "above" signal device of all cars below the floor at which the operated switch is located.

14. In a signal system for a plurality of elevator cars operable past a plurality of floors, a switch at each floor common to all the cars for 10 registering calls for service, an "above" signal device and a "below" signal device in each car, means responsive to an operation of any switch for operating the "below" signal device of all cars above the floor at which the operated switch 15 is located and for operating the "above" signal device of all cars below the floor at which the operated switch is located, and means responsive to the stopping of any car at the floor at which the operated switch is located for cancelling the 20 signals in all cars resulting from said operated switch.

15. In a signal system for a plurality of elevator cars operable past a plurality of floors, a switch at each of said floors common to all the 25 cars for registering calls for service, a pair of signal devices on each car, and means responsive to the operation of any one of the switches to operate the signal devices in each car for indicating a call in the system and for indicating 30 whether the floor at which the switch was operated is above or below the floor at which any given car is located.

16. In an elevator system for operating a car serving a plurality of floors, an up call registering 35 device and a down call registering device for each floor, an energized "above" circuit and an energized "below" circuit, means responsive to the registration of a call for deenergizing that portion of the "above" circuit corresponding to the 40 floors below the registered call and for deenergizing that portion of the "below" circuit corresponding to the floors above the registered call, a signal device in the car, and means responsive to the deenergized portions of said circuits for 45 operating the signal device in the car to indicate the direction of the floor of the registered call relative to the car.

17. In an elevator system for operating a plurality of cars serving a plurality of floors, an up 50 call registering device and a down call registering device for each floor, an energized "above" circuit and an energized "below" circuit, means responsive to the registration of a call for deenergizing that portion of the "above" circuit corresponding to the floors below the registered call 55 and for deenergizing that portion of the "below" circuit corresponding to the floors above the registered call, a signal device in each car, and means responsive to the deenergized portions of the 60 said circuit for operating the signal devices to indicate in the cars the direction of the floor of the registered call relative to the cars.

FRANK E. LEWIS.
